CLAIM

The ornamental design for a faucet as shown and described.

DESCRIPTION

FIG. 1 is a front perspective view of a faucet showing my new design;

FIG. 2 is another perspective view thereof;

FIG. 3 is a front elevational view thereof;

FIG. 4 is a rear elevational view thereof;

FIG. 5 is a left side elevational view showing the opposite handle in an alternate position for clarity of illustration view thereof;

FIG. 6 is a right side elevational view showing the opposite handle in an alternate position for clarity of illustration view thereof;

FIG. 7 is a top plan view thereof;

FIG. 8 is a bottom plan view thereof; and,

FIG. 9 is an enlarged view of encircled portion 9 of FIG. 2. The evenly-spaced broken lines in the drawings depict portions of the faucet that form no part of the claimed design. The dot-dash-dot lines represent boundaries of the enlarged views and form no part of the claimed design.

1 Claim, 9 Drawing Sheets
